INVENTOR.

UNITED STATES PATENT OFFICE.

EDWARD A. CLOONAN, OF ST. LOUIS, MISSOURI.

SCORING ATTACHMENT FOR PRINTING-PRESSES.

1,302,136.

Specification of Letters Patent. Patented Apr. 29, 1919.

Application filed September 12, 1918. Serial No. 253,796.

To all whom it may concern:

Be it known that I, EDWARD A. CLOONAN, a citizen of the United States of America, a resident of the city of St. Louis, in the 5 State of Missouri, have invented certain new and useful Improvements in Scoring Attachments for Printing-Presses, of which the following is a full, clear, and exact description, reference being had to the accompanying drawings, forming a part of this specification.

My invention relates to improvements in scoring attachments for printing presses, one of the objects being to provide a device of this kind adapted to score the paper and at the same time perform the functions of a gripping device for securing the paper to the platen during the printing operation. Another object is to produce a simple 20 scoring device having its scoring elements arranged to form a highly desirable combination of scores in a sheet of paper to be used as a book cover. A further object is to provide a scoring attachment comprising a 25 few simple elements which may be readily adjusted to change the relative positions of the scoring blades. Another object is to produce a scoring attachment of this kind adapted to be adjustably secured to a printing press and adapted to occupy operative 30 positions at a right angle to each other.

With the foregoing and other objects in view the invention comprises the novel construction, combination and arrangement of 35 parts hereinafter more specifically described and illustrated in the accompanying drawings wherein is shown the preferred embodiment of the invention; however, it is to be understood that the invention comprehends changes, variations and modifications which 40 come within the scope of the claims hereunto appended.

Figure I is a fragmentary view of a portion of a printing press equipped with a 45 scoring attachment embodying the features of this invention.

Fig. II is a detail view of the scoring attachment.

Fig. III is a side elevation of the attachment.

Fig. IV is an end view thereof.

Fig. V is a detail view of one of the scoring blades.

Fig. VI is a detail view of one of the separator bars.

To illustrate the manner of attaching the scoring device to a printing press, I have shown a platen, or sheet-receiving table, A provided with ears B, an oscillatory bar C provided with pivot members D mounted in 60 the ears B, and a pair of gripper arms E adjustably mounted on the bar C. The arms E are arranged at a right angle to the bar C, and said bar is preferably provided with longitudinal slots 1 for the reception of 65 bolts 2 whereby the arms E are adjustably secured to the bar C. All of these elements may form part of an ordinary printing press, the gripper arms E being ordinarily used to secure large sheets of paper to the 70 platen A. It will be observed that the arms E, rigidly secured to the bar C, may be turned on the axis of pivot members D so as to move toward and away from the platen A. F designates a sheet of paper 75 mounted on the platen and positioned to be engaged by the printing type (not shown).

The scoring attachment herein shown comprises a marginal frame having longitudinal members 3 and 4, and end members 5 and 6. One end of the longitudinal frame member 4 is recessed to receive a tongue 5' (Figs. II and III) projecting from the end member 5. The opposite end of the longitudinal frame member is provided with a tongue 4' (Figs. II, III and IV) extending into the end member 6. The scoring attachment shown in the drawings is provided with four scoring blades 7 surrounded by the marginal frame and arranged longitudinally thereof. Separator bars 8 arranged longitudinally of the frame are interposed between the scoring blades 7. The several scoring blades and separator bars are detachably secured to 85 the frame by means of screws 9 arranged transversely of the frame and passing through said blades and separator bars. To receive the screws 9, perforations 7' are formed in each scoring blade 7, as shown 90 in Fig. V, and each separator bar 8 is provided with perforations 8'. The head of each screw 9 engages the longitudinal frame member 4, and the threaded ends of screws are mounted in the longitudinal frame member 3.

The scoring blades and separator bars are thus detachably secured to the frame, and they can be readily removed and replaced to locate the scoring blades in different posi- 105 110

tions. Any desired number of scoring blades and separator bars may be used, but in scoring paper book covers I prefer to use four scoring blades, arranged approximately as herein shown, so as to produce four transverse scores across the sheet of paper to be used as a cover.

To more firmly secure the scoring blades and separator bars in the marginal frame, 10 the ends of each scoring blade are recessed as shown at 10 (Fig. V) to receive the tongues 5' and 6' which extend from the end members of the marginal frame, and each separator bar 8 is recessed as shown at 15 10' (Fig. VI) to receive the same tongues. A back web 11, preferably made of sheet metal (Figs. I and III), is secured to the longitudinal frame by means of screws 12 threaded into the longitudinal frame member 3. The scoring blades and separator bars engage the back web 11 at one side of the frame, and the scoring edges of the blades 7 project beyond the opposite side of said frame. 13 designates screws securing 20 the end frame member 6 to the tongues 3' and 4' which extend from the longitudinal frame members 3 and 4. It will be observed that the various elements of the scoring attachment can be very easily taken 25 apart, but when these elements are assembled they are very securely held in position by means of the transverse screws 9, the back web 11, and also by the interlocking connections between the marginal frame and 30 the ends of the scoring blades and separator bars. In Fig. I I have shown the scoring device attached to a printing press so as to engage the sheet of paper F on the platen A. One of the gripper arms E 40 may be provided with a longitudinal slot 14 for the reception of screws 15 whereby the scoring attachment is secured to said arm. The scoring attachment lies at a right angle to the arm E, and the screws 15 may 45 be moved longitudinally of the slot 14 to locate the attachment in different positions relative to the platen. The frame member 5 of the scoring attachment has a shoulder 16 which engages one of the straight longitudinal edges of the slotted arm E.

The scoring attachment can also be secured to the pivotally mounted bar C, instead of being secured to the slotted arm E which lies at a right angle to said bar. 55 A connecting plate 17 (Figs. I, II and III) is preferably used to secure the scoring attachment to the pivotally mounted bar C. This connecting plate may be secured to the frame member 5 by means of the screws 60 15', as shown in Figs. II and III, and said connecting plate preferably has a slot 18 adapted to register with either of the slots 1 in the pivoted bar C. The scoring device may be attached to the bar C as indicated 65 by dot and dash lines in Fig. I, and in this

event the adjacent arm E is preferably removed from the bar C, and the bolt 2 used in securing said arm may also be used to attach the connecting plate 17 to the bar C. The connecting plate 17 is not used when 70 the screws 15 are employed to secure the scoring device to arm E, as shown at the upper portion of Fig. I. However, when the scoring device is secured to bar C as shown by dot and dash lines in Fig. I, the 75 plate 17 is attached by screws 15' (Figs. II and III), and it then forms a detachable extension having a slot 18 adapted to register with either slot 1 (Fig. I). This enables the scoring device to be substituted 80 for one of the arms E.

I claim:

1. A printing press provided with a sheet-receiving platen, a holder comprising a pivotally mounted member and a gripper arm 85 member extending therefrom, said pivotally mounted member being movable to carry said gripper arm member toward and away from said platen, and a scoring device extending from said gripper arm member so 90 as to engage the paper on the platen, said scoring device being at a right angle to said gripper arm member and one end of the extended scoring device being detachably secured to said gripper arm member. 95

2. A printing press provided with a sheet-receiving platen, a holder comprising a pivotally mounted member and a gripper arm member extending therefrom to grip the sheets on the platen, said pivotally 100 mounted member being movable to carry said arm member toward and away from said platen, said members being arranged at a right angle to each other, a scoring device adapted to be selectively secured to 105 either of said members, so as to occupy scoring positions at a right angle to each other, and means for detachably securing said scoring device to said members.

3. A printing press provided with a sheet-receiving platen, a holder comprising a pivotally mounted member and a gripper arm member extending therefrom to grip the sheets on the platen, said pivotally mounted member being movable to carry said arm 110 member toward and away from said platen, said members being arranged at a right angle to each other, a scoring device adapted to be selectively secured to either of said members, so as to occupy scoring positions 115 at a right angle to each other, and means for detachably securing said scoring device to said members, each of said members being provided with a longitudinal slot for the reception of the detachable securing means, 120 and the latter being movable along the slots so as to secure the scoring device in different positions. 125

4. A printing press provided with a sheet-receiving platen, a holder comprising a piv- 130

totally mounted member and an arm member extending therefrom, said pivotally mounted member being movable to carry said arm member toward and away from 5 said platen, a scoring device adapted to extend from either of said members, fastening means for securing said scoring device directly to said arm member, and a detachable extension adapted to connect said scoring 10 device to said pivotally mounted member.

5. In a scoring attachment, a holder comprising a marginal frame, a scoring blade mounted in said marginal frame, a separator bar interposed between said scoring 15 blade and one of the margins of said frame, and detachable clamping means whereby said scoring blade and separator bar are detachably clamped in said marginal frame.

6. In a scoring attachment, a holder comprising a marginal frame, a back web secured to one side of said marginal frame, scoring blades engaging said back web and having scoring edges projecting beyond the 20 opposite side of said marginal frame, separators between said scoring blades, and detachable means whereby said scoring blades are secured to said marginal frame.

7. In a scoring attachment, a rectangular marginal frame, one of the longitudinal 30 members of said frame being detachable, scoring blades surrounded by said frame and arranged longitudinally thereof, longitudinal separator bars mounted between said scoring blades, and means for detachably securing said scoring blades and separator bars in said marginal frame, said means including screws whereby said scoring blades and separator bars are firmly clamped in 35 said marginal frame.

40 8. In a scoring attachment, a rectangular marginal frame, one of the longitudinal members of said frame being detachable; scoring blades surrounded by said frame

and arranged longitudinally thereof, longitudinal separator bars mounted between 45 said scoring blades, and means for detachably securing said scoring blades and separator bars in said marginal frame, said means comprising screws arranged transversely of said frame and passing through 50 said scoring blades, separator bars, and also through the detachable longitudinal member of the frame.

9. In a scoring attachment, a rectangular marginal frame, one of the longitudinal 55 members of said frame being detachable, scoring blades surrounded by said frame and arranged longitudinally thereof, longitudinal separator bars mounted between said scoring blades, and means for detachably securing said scoring blades and separator bars in said marginal frame, said means comprising screws arranged transversely of said frame and passing through 60 said scoring blades, separator bars, and also through the detachable longitudinal member of the frame, the ends of said scoring 65 blades and separator bars being interlocked with the end members of said marginal frame.

70 10. In a scoring attachment, a rectangular marginal frame, one of the longitudinal members of said frame being detachable, scoring blades surrounded by said frame and arranged longitudinally thereof, longitudinal separator bars mounted between 75 said scoring blades, and means for detachably securing said scoring blades and separator bars in said marginal frame, the ends of said scoring blades and separator bars being recessed, and the end members of said marginal frame being provided with tongues which extend into the recesses.

In testimony that I claim the foregoing I hereunto affix my signature.

EDWARD A. CLOONAN.
